DESIGN FOR A PROJECTION APPARATUS

William F. Peck, Snyder, N. Y., assignor to Spencer Lens Company, Buffalo, N. Y., a corporation of New York

Application August 14, 1941, Serial No. 102,835

Term of patent 14 years

To all whom it may concern:

Be it known that I, William F. Peck, a citizen of the United States of America, residing at Snyder, in the county of Erie and State of New York, have invented a new, original, and ornamental Design for a Projection Apparatus, of which the following is a specification, reference being made to the accompanying drawing forming a part thereof.

Fig. 1 is a perspective view of a projection apparatus embodying my design; and

Fig. 2 is a side view thereof, the opposite side being plain.

I claim:

The ornamental design for a projection apparatus, substantially as shown and described.

WILLIAM F. PECK.
